HAIR WAVING MACHINE

William H. H. Davis, San Francisco, Calif., assignor to United States Appliance Corporation, San Francisco, Calif., a corporation of California

Application December 9, 1932. Serial No. 646,362

8 Claims. (Cl. 132—36)

This invention relates generally to machines such as are utilized in beauty parlors for the commercial waving of human hair.

In the past machines for the waving of human hair have commonly utilized an overhead canopy, which serves to suspend a plurality of electrical heaters. This canopy in turn is supported by a portable pedestal or stand. The difficulty with machines of this type is that they occupy considerable room when not in use, and are relatively unsightly. It is an object of the present invention to provide a hair waving machine which can be collapsed into a neat appearing compact structure, when not in use.

15 A further object of the invention is to provide a hair waving machine which can be more readily manipulated by an operator, and which can be more conveniently controlled to secure the desired waving effect.

20 Further objects of the invention will appear from the following description in which a practical embodiment of the invention has been set forth in detail in conjunction with the accompanying drawings. It will be understood that 25 the appended claims are to be accorded a range of equivalents consistent with the state of the prior art.

Referring to the drawings:

Figure 1 is a perspective view, illustrating my 30 machine with its operating parts extended in condition for use.

Fig. 2 is a side elevational view likewise showing the operating parts of the machine extended, and indicating the manner in which these parts 35 are collapsed when the machine is not in use.

Fig. 3 is a cross sectional detail taken along the line 3—3 of Fig. 2.

Fig. 4 is a perspective view, illustrating my machine in collapsed condition.

40 Fig. 5 is a plan view of the machine, with the parts extended.

Fig. 6 is a detail illustrating the manner in which the electrical heaters for waving hair are attached with respect to my machine.

45 Fig. 7 is a sectional view taken on line 7—7 of Fig. 3.

Referring first to Fig. 1 of the drawings, my machine consists generally of a base structure 10, preferably in the form of a cabinet. Secured 50 to the top of cabinet 10, there is a box-like structure 11, which as will be presently explained, may serve to house certain parts of the machine when in collapsed position. The box-like structure 11 is hingedly connected to the 55 cabinet 10 as by means of pivotal connections 12,

so that it can be swung to either a vertical position as shown in Fig. 1, or to a horizontal position overlying the top of the cabinet, as shown in Fig. 4. By means of a conventional brace 13, structure 11 can be releasably locked in its vertical position.

The box-like structure 11 serves as a support for another structure 14, which in turn is adapted to suspend electrical hair waving heaters 16. As will be presently explained, certain mechanical elements so connect structures 11 and 14, that the structure 14 may either be supported in the position illustrated in Fig. 1, or in a collapsed position within the structure 11.

While the details of structure 14 vary in practice, I have found it satisfactory to make it rectangular in contour, as illustrated more clearly in Fig. 5. As illustrated it is a hollow housing made of a suitable insulating material such as a molded phenolic condensate product. Its outer and inner peripheries are apertured, and its interior serves to house electrical contactors and conductors to provide a plurality of electrical outlets. As a suitable manner in which to suspend the electrical heaters 16 from structure 14, I have shown each heater connected to a flexible electric cord 18, which in turn is connected to a plug 19 of the prong type. A loop 21 in flexible cord 18 is frictionally engaged by plug 19, to permit limited vertical adjustment of the heater. Plugs 19 can be detachably applied to structure 14, to make the necessary electrical connections, and to support the heaters in proper operating position. The number of heaters employed can of course be varied to suit different requirements.

The elements which serve to connect structures 11 and 14, are preferably formed as follows:—Yoke 22, formed of a rigid metal tube or bar, has its side portions 23 suitably hingedly connected to the structure 11. Thus as shown more clearly in Fig. 3, each side portion 23 of yoke 22 is provided with a pivotal connection 25, to a vertical wall 24 fixed within structure 11. Thus the axis of the pivotal movement of yoke 22 with respect to structure 11 is horizontal, and is parallel to the pivotal axis of structure 11 upon the cabinet 10. In order to releasably lock yoke 22 in an extended position as illustrated in Fig. 1, a flange 26 is secured to each portion 23, and each of these flanges is slotted to receive a lug 27. Lugs 27 are each carried by a sliding rod 28, one end of which is provided with an outer knob 29. Compression spring 31 serves to urge rod 28 in one direction, thus serving to maintain lug 27 in locked position with respect

to flange 26, until released by pulling outwardly upon knob 29.

Journaled to the intermediate and horizontal portion 33 of yoke 22, there is a sleeve 34. Fixed to sleeve 34, there is a pair of spaced parallel rods or arms 36. Swinging movement of arms 36 with respect to yoke 22 is limited, as by means of pins 37 fixed to yoke 22, which are accommodated within segmental recesses 38 formed in the ends of sleeve 34. The amount of swinging movement thus permitted should be at least about $\frac{1}{4}$ of a circle, or through the arc indicated in Fig. 2. The connection between arms 36 and structure 14 is preferably a sliding one, to permit this structure to be slid to a position relatively close to sleeve 34 before the collapsing operation to be presently explained. Arms 36 are provided with enlarged heads 41, to prevent disengagement of this sliding connection.

Before describing the manner in which my machine may be collapsed and extended in an operating position, certain features of the box-like structure 11 must be described in greater detail. The side wall 42, which is uppermost when structure 11 is in a horizontal position as viewed in Fig. 4, is provided with a hinge connection 43 with the main body of structure 11. Likewise the wall 40 of structure 11, which forms the front wall as viewed in Fig. 4, is provided with slots 43a to accommodate the portions 23 of yoke 22. The wall 44, which forms the bottom of structure 11 as viewed in Fig. 4, or the front of the structure as viewed in Fig. 1, preferably forms an instrument panel for switches or other control devices utilized in operating the machine. Thus as shown in Fig. 1, mounted upon wall 44 are the electrical switches 46, and the control device 47, which may be a time control switch.

Operation of my machine can be described briefly as follows:—While the machine is in operation its parts are positioned substantially as illustrated in Fig. 1. If the operator now wishes to collapse the machine, the heaters 16 are removed from structure 14, and this structure is then slid towards sleeve 34. Following this operation knob 29 is now pulled outwardly to permit yoke 22 to swing backwardly and downwardly with respect to the structure 11. At the same time by virtue of the journaling of sleeve 34 upon yoke 22, structure 14 swings relative to the yoke, so that when yoke 22 is in its lowermost position and within structure 11, structure 14 can be swung upwardly and inwardly into structure 11, between the portions 23 of the yoke. It is of course evident that when the parts are being swung into structure 11, wall 42 is in a horizontal or open position. Thereafter wall 42 is swung to closed position, and then structure 11 is swung down to horizontal position as shown in Fig. 4. In replacing the machine in position for a waving operation, substantially the same operations are followed in reverse order, except that yoke 22 is automatically locked in extended position.

In the above described mode of operation, I have referred to removal of the heaters from structure 14, before collapsing this structure within the structure 11. It is of course evident that structure 11 can be made of sufficient dimensions that it can house all of the heaters required in a permanent waving operation. When extended, the controls on panel 44 are readily accessible and the top of the cabinet 75 is also available. When collapsed the machine

is neat in appearance and relatively compact.

I claim:

1. In a hair waving machine, a base structure, an electrically wired structure to which electrical hair waving apparatus may be connected, and collapsible means connecting said structures whereby said second structure may be either retained in an elevated operating position or in a collapsed out of the way position. 80

2. In a hair waving machine, a base structure, an electrically wired structure to which electrical hair waving apparatus may be connected, and collapsible means connecting said structures whereby said second structure may be either retained in an elevated operating position or in a collapsed out of the way position, said collapsible means comprising a plurality of elements hingedly connected together. 85

3. In a hair waving machine, a base structure, a box-like structure hingedly connected to the upper portion of the base structure and adapted to be positioned either substantially vertically, or in an out of the way position, a third structure from which hair waving heaters may be suspended, and collapsible means connecting said third structure with said box-like structure, whereby when the box-like structure is in a vertical position the third structure may be supported thereby in an elevated operating position, and when the box-like structure is in an out of the way position the third structure may be collapsed within the same. 95

4. In a hair waving machine, a cabinet-like base structure, a box-like structure hingedly connected to the base structure and adapted to be positioned either substantially vertically or substantially horizontally upon top of the base structure, a third structure from which hair waving heaters may be suspended, and collapsible means connecting said third structure with said box-like structure, whereby when the box-like structure is in a vertical position the third structure may be supported thereby above the box-like structure and to one side thereof, and when the box-like structure is in a horizontal position the third structure may be collapsed and housed within the same. 110

5. In a hair waving machine, a base structure, a box-like structure hingedly connected to the base structure and adapted to be positioned either substantially vertically or in an out of the way position, a third structure from which hair waving heaters may be suspended, a mechanical element forming a link which is pivotally connected to said box-like structure, another mechanical element having a hinge connection to the first mechanical element, said third structure having a sliding connection with said second mechanical element, said mechanical elements being so coordinated with respect to the box-like structure, that when the box-like structure is in a vertical position said third structure may be supported outside said box-like structure in an elevated operating position, and when said box-like structure is in an out of the way position 130 said mechanical elements together with said third structure may be collapsed within the same. 125

6. In a hair waving machine, a cabinet-like base structure, a box-like lid structure for said base structure, a hinge connection between the rear horizontal edge of said lid structure and the corresponding edge of said cabinet structure, whereby said lid structure may be swung to either a vertical position, or to a horizontal 145 150

out of the way position upon top of the cabinet-like structure, a third structure from which hair waving heaters may be suspended, and means for supporting said third structure with respect to said lid structure, said means including elements collapsibly connected together whereby said third structure may be supported in an operating position elevated with respect to said lid-like structure and to the rear thereof, or may be collapsed within said lid-like structure.

7. In a hair waving machine, a cabinet-like base structure, a box-like lid structure disposed upon said cabinet-like structure, means forming a hinge connection between the rear horizontal edge of said lid structure and the corresponding upper edge of said cabinet-like structure, whereby the lid structure may be swung to either a vertical position or to a horizontal position overlying the cabinet-like structure, a yoke having its ends pivotally connected to the lid-like structure, whereby when said lid-like structure is in

a vertical position, said yoke may be swung to a position in which it extends upwardly from said lid-like structure, or to a collapsed position in which it is housed within said lid-like structure, a third structure in which hair waving heaters are adapted to be suspended, means forming a hinge connection between said third structure and said yoke, whereby said third structure may be supported in operating position or may be collapsed together with said yoke within said lid-like structure.

8. In a hair waving machine, a cabinet-like base structure, an electrically wired structure to which hair waving apparatus may be connected, and extensible supporting means connecting said structures whereby said second structure may be either retained in an elevated operating position offset laterally to the rear of the base structure or in an out-of-the-way position adjacent the upper portion of the base structure.
